UNITED STATES PATENT OFFICE.

EDWARD H. KENNEY AND ELIZABETH KENNEY, OF PHILADELPHIA, PENNSYLVANIA.

FLYING PENNANT.

Application filed October 12, 1921. Serial No. 507,229.

To all whom it may concern:

Be it known that we, EDWARD H. KENNEY and ELIZABETH KENNEY, citizens of the United States, residing in Philadelphia, Pennsylvania, have invented a Flying Pennant, of which the following is a specification.

The object of this invention is to provide a novel structure combining the characteristics of a kite with those of a pennant, the elements of the structure being permanently united yet relatively movable to permit folding into a packet of relatively small dimensions, and the arrangement of the elements being such as to greatly facilitate the setting up of the structure into kite form and the partial folding or unfolding into the form of a pennant.

The invention will be more readily understood by reference to the accompanying drawings, in which:

Figure 1, is a view in perspective of the kite set up;

Fig. 2, is a rear view of the kite illustrating one of the steps in the folding operation;

Fig. 3, is a view of the kite partially folded and illustrating the pennant feature of the kite, and

Fig. 4, is a view of the kite completely folded.

With reference to the drawings, 1 and 2 indicate respectively elements which together constitute the framework of the structure, said elements being pivotally connected so as to be relatively movable to positions at right angles to each other or into substantial alignment.

As clearly shown, the pin 3 which pivotally secures these elements together passes through the approximate center of the element 2 and through the element 1 near one end thereof; but regardless of the dimensions of these elements or rods and the points thereof through which the pin passes, it is essential for the purposes of this invention that the element 1 on at least one side of the pivot be longer than one-half the length of the element 2.

Secured in permanent fashion to the element 2 is a quadrilateral fabric element 4, substantially V-shaped portions 4^a and 4^b of which extend on either side of the element 2, the portion 4^a being in the present instance smaller than the portion 4^b.

Secured in suitable manner as by means

of pins or nails 5, 5, to the ends of the element 2 is a cord, or cords, 6, said cord extending along and being secured to the edges of the fabric element 4 and constituting a bounding cord for the said fabric. Portions of the fabric element 4 at the apexes of the respective V-shaped portions 4^a and 4^b are cut away to expose the bounding cord 6 at these points, and thereby permit detachably securing the cord 6 to the ends of the frame element 1. In the present instance, there is established in each end of this latter element 1 a pair of pins 7, 7, between which the cord is adapted to pass and be retained. In completing the structure, a cord 8 of less length than the element 2 is secured to one of the pins 5 in the ends of said element 2, and has a loop 9 at the opposite end which is adapted to be passed over the pin 5 in the opposite end of the element 2; while a second cord 10 is secured to one end of the element 1 and has at the other end means such as a loop for detachably securing that end to the opposite end of the element 1; all as shown in Fig. 1.

In this latter figure, we have illustrated our structure set up in the form of a kite, the bounding cord 6 being passed between the respective sets of pins in the opposite ends of the element 1, which is disposed at right angles to the element 2; the free end of the cord 10 being attached to the corresponding end of the element 1 and passing across the face of the kite; and the loop 9 of the cord 8 being passed over one of the pins 5 in the element 2, and by reason of its inferior length bowing the element 2 outwardly, as clearly illustrated. The cord 10 constitutes means for attaching a cord 11 to the kite. 95

In taking down the kite to convert the structure to its pennant form or to completely fold it up, the operation consists in first releasing the loop 9 from the pin 5 over which it passes and the free end of the cord 10 from the end of the element 1 to which it is temporarily secured; thereafter releasing the cord 6 from the ends of the frame element 1 by removing the said cord from between the sets of pins 7, 7; 100 moving the element 1 around the securing pivot 3 into alignment with the element 2, as illustrated in Fig. 2; and, if it is desired to take advantage of the pennant feature of the structure, folding the portion 4^a of the fabric around the aligned elements 1 and 2 in the manner illustrated in

Fig. 3, which latter figure illustrates the structure in its pennant form, or otherwise securing the said portion to the elements or to the portion 4^b. Complete folding of the structure can thereafter be accomplished by folding the portion 4^b of the fabric around the elements 1 and 2, as illustrated in Fig. 4.

The fabric element 4 may, of course, be made in any color or combination of colors 10 for the purpose of the pennant, as well as adding attraction to the kite.

The bowing cord 8 may be folded inwardly with one or other of the portions 4^a or 4^b of the fabric element, or may be 15 utilized to bind the fabric to the frame elements when the structure is completely folded, also as shown in Fig. 4.

The structure as a kite will be found to possess manifold advantages over folding 20 kites of the usual form, particularly in the extreme facility with which it may be set up, it being a simple matter to secure the bounding cord to the ends of the element 1 and the loop 9 of the bowing cord to the end 25 of the element 2, and equally as simple to release them. The structure further has the considerable advantage of the pennant feature, which materially enhances the sales value of the article.

30 We claim:

1. A folding structure comprising a pair of elongated elements pivotally secured together substantially at the center of one and near an end of the other, a fabric member 35 secured to and having portions extending at each side of the first of said elements, and co-operating means on said extending portions and at the ends of the second of said elements for detachably securing the said 40 fabric member to the latter element.

2. A folding structure comprising a pair of rods pivotally secured together substan-

tially at the center of one and near an end of the other, a fabric member secured to and having portions extending at each side 45 of the first of said elements, a bounding cord for said member, and means at the ends of the second of said elements for detachably securing the bounding cord thereto.

3. A folding structure comprising a pair 50 of rods pivotally secured together substantially at the center of one and near an end of the other, a fabric member, a bounding cord extending around the edge of the fabric member and secured to the ends of the 55 first of said elements, and means at the ends of the second of said elements for detachably securing the bounding cord thereto.

4. A folding structure comprising a pair of rods secured together substantially at 60 the center of one thereof and adapted for relative movement into positions at right angles to each other and into substantial alignment, that portion of the other of said rods to one side of the pivot being longer 65 than one-half the length of the first, a fabric member secured to and having portions extending at each side of the said first element, and co-operating means on said extending portions and at the ends of the second of said elements for detachably securing the said fabric member to the latter element.

5. A folding structure comprising elements permanently secured together and 75 relatively adjustable into the form of a framework for a kite and into substantial alignment to constitute the staff of a pennant, and a fabric member adapted to be attached to the elements and to constitute 80 both the fabric of the kite and the pennant.

EDWARD H. KENNEY.
ELIZABETH KENNEY.
